(57) CLAIM

The ornamental design for a brush as shown and described.

DESCRIPTION

FIG. 1 is a front top perspective view of the brush showing my new design;

FIG. 2 is a side view thereof;

FIG. 3 is another side view thereof;

FIG. 4 is a top plan view thereof;

FIG. 5 is a bottom plan view thereof;

FIG. 6 is another side view thereof; and,

FIG. 7 is another side view thereof.

The broken lines in the drawings illustrate portions the brush which form no part of the claimed design.
